UNITED STATES PATENT OFFICE.

CLARENCE J. WESTON, OF FORT DODGE, IOWA.

CONVEYING-RECEPTACLE.

1,378,574.

Specification of Letters Patent.

Patented May 17, 1921.

Application filed January 2, 1920. Serial No. 349,031.

To all whom it may concern:

Be it known that I, CLARENCE J. WESTON, a citizen of the United States, residing at Fort Dodge, in the county of Webster and 5 State of Iowa, have invented a certain new and useful Conveying-Receptacle, of which the following is a specification.

My invention relates to conveying receptacles of the class in which the body is 10 made in two transverse sections hinged together at their tops, and wherein the dumping of the contents of the car is effected by unlatching the hinged sections and allowing them to drop downwardly and apart.

15 It is my object to provide in connection with a conveying receptacle of this type, means whereby the hinged sections may be automatically unlatched by engagement with a trip lever permanently stationed at a de- 20 sired point on the track.

A further object is to provide means whereby the hinged sections can be automatically righted after the contents have been dumped.

25 With these and other objects in view, my invention consists in certain details, in the construction, arrangement and combination of the various parts of the device, whereby the objects contemplated are attained, as 30 hereinafter more fully set forth, pointed out in my claims, and illustrated in the accompanying drawings, in which:

Figure 1 shows a side elevation of my improved conveying receptacle in position for 35 dumping.

Fig. 2 shows a similar view of the receptacle in closed position.

Fig. 3 shows an inverted plan view of my improved conveying receptacle.

40 Fig. 4 shows a rear elevation of the same; and

Fig. 5 shows a detail view of the adjustable means for raising the sections.

Referring in detail to the accompanying 45 drawings, I have used the reference numeral 10 to indicate the wheels of the receptacle; 11 the hinged sections comprising the body, and 12 the track upon which the car is operated.

50 Arranged transversely of the receptacle at the outer end of one of the sections is a crank shaft 13 mounted in bearings 14 and provided with crank arms 15 extending upwardly or downwardly at either side of the 55 receptacle. A rod 16 is extended through

the crank arms. Pivoted to either end of the rod 16 is a link 17 arranged longitudinally at the sides of the receptacle and extending forwardly to a point near the inner end of the adjacent section, where it 60 is pivoted to an upwardly extending arm 18 formed on a hook shaped lever 19. One end of the rod 16 is projected outwardly beyond the side of the lower portion of the receptacle, as shown at 20, and a bracket 65 21 fixed to the link 17 is employed for bracing the projected end of said rod.

A contractible coil spring 22, fixed at one end to the side of the body and at the other end to one of the links 17, is employed 70 for yieldingly holding the links 17 in their forward position. The lever 19 is pivoted to the side of the body section as at 23 and extends forwardly to the abutting body section where it is normally in engagement 75 with a roller 24 carried on a stud 25 fixed to the adjacent body section. In this manner the lower adjacent ends of the hinged body sections are held together in position for receiving their load.

80 Secured to the upper parts of the sides of the sections near their inner ends on each side of the car, are bars 25^a and 25^b, extending upwardly and toward each other when the car is in normal position. The arms on 85 the two sections on the respective sides of the car are pivoted together at their ends.

For automatically releasing the hook shaped levers to thereby dump the car, the following means is provided: located at the 90 desired point on the track is a standard 26 preferably secured to a tie and extending beneath the adjacent rail as shown in Fig. 4. A trip lever 27 is pivoted to the standard with one end projecting upwardly and 95 having pivoted to its lower end an arm 27^a provided with a weight 28. On the arm 27^a is a stop 27^b arranged to coact with the arm 27 to limit pivotal movement of the arms 27 and 27^a relative to each other. 100

All of these parts are arranged at the side of the track in position to clear all parts of a passing car save the projecting end 20 of the rod 16. This end of the rod is designed to be engaged by the upwardly extending end of the lever 27 as the car is moved along the track. A chain 28^a and strong spring 28^b are connected with the arm 27^a and a fixed member, and together with the lever 27 are sufficient to hold said lever 110

when the rod 16 engages its upper end and thereby the rod will be moved rearwardly on the crank arms, carrying with it the links 17, thereby raising the hook shaped levers 5 upwardly and out of engagement with the roller sleeved lugs. If the car moves farther the weight is lifted before any parts are broken to permit the car to clear the arm 27. When the car moves in the opposite 10 direction, the lever arm 27^a swings on the arm 27 without lifting the weight in such a way as to do harm.

Obviously the body sections will part at their lower ends when the hooks have been 15 released, and will thereupon drop to the position shown in Fig. 1 of the drawings.

For returning the body sections to their closed position, the following means are provided. Positioned near the center of the 20 track at a point in advance of the dumping position of the car is a roller 29 mounted in a standard 30, which standard is permanently fixed to one of the ties on the track. Beneath one of the body sections near its 25 inner end and in line with the roller 29 is secured an erecting cam 31. As the car is moved forwardly along the track the roller 29 is engaged by the erecting cam 31, see Fig. 1, and the body section is thereby 30 moved upwardly, carrying the adjacent section with it. As the sections are moved upwardly and toward each other, the beveled end 33 of the hook shaped lever 19 will move over the roller 24 on the stud 25 until the 35 roller enters the hook portion of the lever. The rod 16 and the spring 22 operate to hold the hook shaped lever 19 always in position to effect a contact of the beveled end of the lever and the roller 24, so that 40 in returning the body sections to their closed positions an engagement of the hook shaped lever and the roller is always assured.

Mounted upside down in the lower part of the cam 31 is a round headed screw-threaded 45 bolt 32 capable of adjustment by means of washers, so as to engage the roller 29 and insure the final raising movement of the car sections in spite of any variations in the positions of the cam and the roller 29, due 50 to wear and so forth.

On each car section is a stop device 100 adapted to engage the track and limit the dumping movement of the sections.

In practical operation, it will be seen that 55 when the car is filled and moved along the track to the point where it is desired to dump the contents thereof, the trip lever 27 will unlatch the sections and permit them to drop to their dumping positions. In the 60 act of dumping the projecting end of the rod 16 will be raised enough to pass over the lever 27, and the cam 31 will, after the car has traveled a short distance, engage the roller 29 and thereby the parted sections will be moved to their closed positions.

The car then may be continued in the same direction for another load, or, if desired, it may be returned over the same track and in this latter case, the erecting track will slide over the roller 29 without interference, 70 while the trip lever 27 will be easily swung a sufficient distance to permit the projecting end of the rod 16 to pass over it.

The advantages offered by my improved car are obvious, for it is seen that the operations of dumping and righting the car are entirely automatic requiring no attention whatever from the operator. The simplicity and arrangement of the several parts of my device render possible a durable and inexpensive construction, which are also advantages in a device of this class. 75

My improved dumping and erecting means are particularly adapted for use in connection with a string of cars, and as the string of cars is moved in one direction along the track the cars will successively dump and right themselves in the manner described. 80

It is to be understood that many changes 90 in the details of the construction of my device may be made without departing from the spirit of my invention.

I claim as my invention:

1. In a device of the class described, the 95 combination of a car, comprising sections hinged at their tops, means for detachably securing said sections together at their lower inner ends, an erecting cam fixed beneath the inner end of one of said sections, and a roller carried on a standard fixed in the path of said car for engaging said erecting cam to thereby move the detached sections to their closed position, said cam having an 100 adjustable member. 105

2. In a device of the class described, the 110 combination of a car, comprising two sections hinged at their upper ends, lugs fixed on opposite sides of one of said sections near its lower inner end, hook shaped levers 115 on the adjacent section in engagement with said lugs, a link pivoted to each of said hook shaped levers and extending longitudinally to the outer end of said section, a crank shaft on the end of said section having vertically extending arms pivoted to said links, and a trip lever positioned in the path of said car to engage said crank shaft and thereby disengage said levers from the lugs. 120

3. In a device of the class described, the 125 combination of a car, comprising two sections hinged at their upper ends, lugs fixed at opposite sides of one of said sections near its lower end, hook shaped levers on the adjacent section in engagement with said lugs, a link pivoted to each of said hook shaped levers and extending longitudinally to the outer end of said section, a shaft on the end of said section, vertically projecting 130

arms on said shaft, a rod extended between said vertically projecting arms and having one end thereof extended beyond the side of said car and pivoted near its ends to said 5 links, and a trip lever stationed in the path of the projecting end of said rod for engaging it to thereby disengage said hook shaped levers from the lugs.

4. In a device of the class described, the 10 combination of a car, comprising two sections hinged at their upper ends, lugs fixed at opposite sides of one of said sections near its lower end, hook shaped levers on the adjacent section in engagement with said 15 lugs, a link pivoted to each of said hook shaped levers and extending longitudinally to the outer end of said section, a shaft on the end of said section, vertically projecting arms on said shaft, a rod extended between 20 said vertically projecting arms and having one end thereof extended beyond the side of said car and pivoted near its ends to said links, a standard positioned at one side of the path of said car, and a weighted lever 25 pivoted to said standard to engage the projecting end of said rod and thereby move it rearwardly for disengaging said hook shaped levers from the lugs.

5. In a device of the class described, the 30 combination of a car, comprising sections hinged at their tops, means for detachably securing said sections together at their lower inner ends, and means operated by an erecting roller positioned in the path of 35 said car for moving said sections to closed position when they have been detached.

6. In a device of the class described, the 40 combination of a car, comprising sections hinged at their tops, means for detachably securing said sections together at their lower inner ends, an erecting cam fixed beneath the inner end of one of said sections, and a roller carried on a standard fixed in the path of said car for engaging said erecting 45 cam to thereby move the detached sections to their closed position.

7. In a device of the class described, the 50 combination of a car, comprising sections hinged together at their upper inner ends, lugs fixed to opposite sides of one of said sections near its lower inner end, hook shaped levers on the adjacent section in engagement with said lugs, means for disengaging said levers from said lugs, and means 55 operated by a roller positioned in the path

of said car for moving said sections to position where the levers reengage said lugs.

8. In a device of the class described, the combination of a car, comprising sections hinged together at their top, lugs fixed to 60 opposite sides of one of said sections near its lower inner end, hook shaped levers on the adjacent section in engagement with said lugs, spring actuated links connected with said levers and extending longitudinally to the outer end of the adjacent section, a crank shaft carried on the outer end of said section and pivoted to said links, means stationed in the path of said car to engage said crank shaft and thereby disengage the hook shaped levers from the lugs, an erecting cam fixed beneath the inner end of one of said sections, and an erecting roller in the path of said car in position to be engaged by said cam for moving said sections to their closed position when they have been disengaged.

9. In a device of the class described, the combination of a car, comprising two sections hinged together at their upper inner 80 ends, lugs on opposite sides of one of said sections near its lower inner end, hook shaped levers pivoted to the adjacent section and designed to engage said lugs, said hook shaped levers being each provided 85 with a beveled end, a link pivoted to each of said hook shaped levers and extending longitudinally along the adjacent body section to the outer end thereof, a spring for yieldingly holding said links in their forward positions, a shaft mounted on the outer end of the body portion adjacent to said links, vertically extending arms on the ends of said shaft, a rod extended between said vertically extending arms and fixed to 90 said links, one end of said rod being projected outwardly beyond the side of the car, a standard stationed at one side of the path of said car, a weighted lever pivoted to said standard and in position to be engaged by the projecting end of said rod,

95 an erecting track fixed to the bottom of one of said sections at its inner end, a second standard fixed in the path of said car, and a roller mounted in said second standard in position to be engaged by said erecting track, all substantially as and for the purposes stated.

Des Moines, Iowa, November 29, 1919.

CLARENCE J. WESTON.
